UNITED STATES PATENT OFFICE

ALFRED R. WILSON, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed February 3, 1930. Serial No. 425,578.

The invention relates to car roofs of the flexible all-metal type and has more particular reference to the construction applicable to cars which are provided with end doors. With this type of car it is necessary to provide a full height door opening which in turn necessitates an abnormal construction of end plate for the car roof frame. This end plate is in the form of an inverted channel beam which is sufficiently elevated above the plane of the roof to give the necessary strength without trespassing on the required clearance for the door opening. Thus to apply the flexible roof to this type of car I have devised a construction as hereinafter set forth.

In the drawings:

Figure 1 is a plan view;

Figure 2 is a longitudinal section on line 2—2 of Figure 1;

Figure 3 is a similar view on line 3—3 of Figure 1;

Figure 4 is an end elevation of the arched end plate; and

Figure 5 is a section on line 5—5 of Figure 1 showing said arched end plate from the opposite side.

The usual construction of flexible all-metal car roofs comprises a skeleton roof frame composed of carlines and purlines upon which are laid roofing sheets having upstanding flanges at their sides and ridge end. Between these sheets are ridge caps, transverse caps and junction caps which serve to hold the sheets down upon the roof frame and to thoroughly weatherproof the same. At the end of the car it is usual to provide a sheet having a down-turned flange which overlaps the end plate of the car roof frame. Where, however, the car is provided with an end door and a specially constructed end plate, the usual construction of roof is not applicable.

As shown in detail, A are the side plates of the roof frame and B is the specially constructed end plate for the end door opening. This end plate is of inverted channel cross section having on its inner side a laterally extending flange C which conforms generally to the slope of the roof. Adjacent to this

flange is an upwardly extending portion D which at the ridge extends only a slight distance above the roofing sheets but at the eaves and intermediate the eaves and the ridge is a greater distance above the plane of the sheets. The lower edge of the wall E is also preferably reinforced by a Z-bar F which extends inwardly therefrom. The laterally extending flange C on the inner side of the channel portion is slightly below the plane of the roofing sheet and extends to the sides of the car where it is attached to the side plates A. This flange is preferably flared adjacent to the side plates as indicated at C' to form a gusset terminating in a down turned flange C² which is riveted to the web of the side plate A. The ridge pole H is supported at its end upon the center portion of the flange C and purlines I are supported upon brackets I' also secured to the flange C. 70

As has been stated, it is usual with flexible car roofs to have an end roofing sheet which is bent downward over the end plate of the roof frame. Inasmuch however, as the end plate B extends upward above the plane of the car roof, such a construction of end sheet can not be used and I have substituted therefor the following: J is a roofing sheet which extends between the end plate B and the next adjacent carline K. This sheet is preferably supported upon the ridge pole H and the filler strips L on the purlines I, together with wooden supporting strips M on the flange C. The filler strips L are preferably inclined so as to pitch the sheet slightly downward towards the end of the car. This is for the purpose of directing the water shed from the sheet towards the end plate B where it is over the flange C and gusset C'. The said sheet is preferably panned to form upstanding flanges J' at its sides and at the ridge with a downturned eaves flange J². A portion of the latter overlies the downturned flange C² of the end plate while another portion J³ is provided with a return bent flange J⁴ for engaging an eaves flashing J⁵. Thus the water shed from the portion of the plate which does not overlie the flange C and gusset C' is prevented by the flashing J⁵ from finding access to the interior of the car while 90

95

100

the flange C prevents access by the water shed from the other portion of the sheet.

For weatherproofing between the sheet J and the end plate B there is provided a cap 5 N which embraces the channel portion of said end plate and is riveted or otherwise secured thereto. On its inner side this cap has a depending flange N' spaced from the portion D of the end plate and also from the 10 upstanding flange J' so as to permit limited freedom of movement of said sheet. A laterally extending flange N² at the lower edge of the flange N' bears on the sheet and serves to hold it down as well as to weatherproof 15 the same. On its outer side the cap N has a downturned flange N³ which overlaps a facie O secured to the portion E. P is a ridge cap which embraces the upstanding ridge flanges of the sheet J and the cap N and fashioned 20 to embrace this ridge cap P, being weatherproofed by a packing P' formed of canvas or other suitable material. The weatherproofing for the opposite edge of the sheet J is of the usual construction comprising a cap Q 25 for embracing the carline K.

With the construction as described the sheet J will have the same degree of flexibility as the other roofing sheets and will form a weatherproof joint with the end plate 30 B. Due to the fact that the plate is inclined slightly toward this end plate the greater portion of the water shed by this plate will be directed over the flanges C and C' thereby being prevented from finding access to the 35 interior of the car.

What I claim as my invention is:

1. The combination with a railway car having an end door, of an arched end plate above said door having a portion extending 40 above the plane of the roofing sheets with a laterally extending flange on its inner side below the plane of said sheets, a carline, a roofing sheet between said carline and end plate having a portion overlapping said 45 flange with an upstanding flange adjacent to the upwardly extending portion of said plate and a weatherproofing cap embracing the upstanding portion of said plate and said upstanding flange.

2. The combination with a railway car having an end door, of an arched end plate above said door having a portion extending upward above the plane of the roofing sheet with a laterally extending flange on its inner 55 side below the plane of said sheet, said flange extending to the eaves of the car and secured to the side plate thereof, a carline and a roofing sheet intermediate said carline and end plate having an upstanding flange adj- 60 cent to the upwardly extending portion of said end plate and overlapping said laterally extending flange, said sheet being inclined longitudinally of the car to direct the water shed therefrom over said flange, and a 65 weatherproofing cap embracing the upward-

ly extending portion of said end plate and upstanding flange of said sheet.

3. The combination with a railway car having an end door, of an arched end plate above said door and having a portion of inverted channel cross section extending upward above the plane of the roofing sheet with a laterally extending flange on its inner side below the plane of said sheet, said flange extending to the side of the car and being 70 enlarged in width adjacent to said side to form a gusset secured to the side plate of the car, a carline and a roofing sheet between said carline and end plate provided with upstanding flanges at its opposite sides, a 75 portion of said sheet overlying the flange on said end plate and provided with a downturned eaves flange, a weatherproofing cap embracing said end plate and upstanding flange of the sheet and a support for said sheet inclined longitudinally of the car to 80 direct the water shed therefrom over the flange of said end plate.

4. The combination with a railway car having an end door, of an arched end plate 90 above said door having a portion of inverted channel cross section extending upward above the plane of the roofing sheet with a laterally extending flange on its inner side below the plane of the sheet, said flange extending to the side plate of the car and being secured thereto, a carline and a roofing sheet between said carline and end plate, said sheet being panned to form upstanding flanges at 95 its sides and at the ridge, a ridge cap for 100 embracing the ridge flange of said sheet and transverse caps for embracing the side flanges of said sheet, one of said caps also embracing the upwardly extending portions of said end plate and the ridge cap.

In testimony whereof I affix my signature.
ALFRED R. WILSON.
